Inventor:

UNITED STATES PATENT OFFICE.

WILLIAM C. J. GUILFORD, OF HARRISON, MAINE.

PASSIVE MASSAGE IMPLEMENT.

1,253,281.

Specification of Letters Patent. Patented Jan. 15, 1918.

Application filed May 18, 1916. Serial No. 98,351.

To all whom it may concern:

Be it known that I, WILLIAM C. J. GUILFORD, citizen of the United States, residing at Harrison, in the county of Cumberland and 5 State of Maine, have invented certain new and useful Improvements in Passive Massage Implements, of which the following is a specification, reference being had therein to the accompanying drawing.

10 This invention relates to massage implements and has for its primary object provision of a tool capable of being applied to practically any part of the body and to be manually shifted over the surface of the 15 body by subjecting the parts being traversed to a passive manipulating and exercising action.

Broadly, the invention embraces a pair of 20 massage elements supported from a handle part, the massage elements being adapted to engage the part of the body to be treated at separated points and to be alternately actuated to correspondingly affect the part under treatment. Preferably, the massage 25 elements are of a pneumatic character.

More specifically the invention contemplates the mounting of the massage elements in free pivotal association with suitable supporting arms, the latter being desirable, 30 though not necessarily connected to the above mentioned handle part so as to swing to and to be held in adjusted positions to vary the distance of the massage elements apart in keeping with the part of the body 35 or surface thereof to be treated.

Details in the construction and arrangement of parts constituting one embodiment of the present invention will be better understood from the specific description hereinafter contained when read in connection 40 with the accompanying drawings forming part hereof and wherein the preferred embodiment of the invention is illustrated.

In the drawings:

45 Figure 1 is a perspective view of the apparatus complete;

Fig. 2 is an end view of the massage device;

Fig. 3 is a side view;

50 Fig. 4 is a longitudinal section through one of the massage elements and its support;

Fig. 5 is a sectional view through the handle;

Fig. 6 is a longitudinal sectional view of 55 one of the massage elements showing the handle and associated parts separated; and

Fig. 7 is a fragmentary elevation.

Referring more specifically to the drawings wherein like reference characters designate the same parts in the several views, 60 A and B represent in a general way the expandable massage elements forming part of my improved tool, from which flexible rubber hose connections C lead to an actuator designed to expand and contract said 65 expandable elements, the particular type of such actuator, so long as the same can, when desired, relatively alternate the expansion and contraction of the massage elements not being essential to a full presentation of the 70 present invention, suitable types of actuators however being illustrated in detail in my two companion cases executed of even date herewith, Serial No. 98,350 and Serial No. 93,352, dealing on the one hand with a 75 manually driven actuator and on the other hand with a motor driven actuator. Here, I have shown in a general way the latter style or motor driven actuator the same including a base D on which an air storage 80 tank E is mounted having valve controlled pipe connections F leading to cylinders G suitably supported on the base D, the cylinders containing pistons as shown in dotted lines at H alternately reciprocated through 85 oppositely arranged cranks J connected by piston rods with the pistons, and driven through suitable gearing represented by dotted lines at L from a motor M receiving its 90 energy from a convenient source of power.

By filling the cylinders and pipe connections leading to the expandable elements with air from the tank E, and closing the valves in the pipe connections running from the tank an air column is presented in advance of the pistons G adapted to be moved back and forth in keeping with the operation of the pistons and in an alternate manner with respect to each other to exert the desired expanding action on the massage 100 elements and permitting said elements to retract as the case may be.

The massage elements comprise base members N on the inner faces of which are rubber sheets O sealed around the marginal 105 portions thereof to the base members by detachable retaining frames P and the special construction of which need not be here pointed out inasmuch as the same constitutes the subject matter of my pending application directed to the abdominal massaging devices Serial No. 98353; and the same

is true of the coupling members Q connecting the air conductor or pipes C through the base members N and with the space between the base members and the expanding 5 rubber sheet or diaphragm.

- The base members N are transversely curved in the present instance, instead of longitudinally curved as in my said companion case, it being here the intention to 10 manually shift the massage device along the limbs or arms, or in fact other portions of the body, the curvature of the base members conforming in shape to the curved surfaces over which they are intended to ride. 15 It is desired that the massage elements A and B may have a freedom of movement, or capability of self adjustment to the member or part of the body to be treated and to this end the base members at the upper outside 20 portions thereof are pivotally connected, through the medium of the screw eyes or the equivalent, as represented at R, to the offset ends s of a pair of arms S arranged at right angles to the longitudinal axes of the 25 massage elements and at their outer ends connected to a handle T extending lengthwise of the massage elements and located in front of the same with abundant space therebetween to accommodate the hand of 30 the operator.

The arms S at their outer ends are flattened and formed into apertured ears U U' sleeved upon the threaded stem t of the handle T, the ear U having a perforation u 35 to engage a pin u' rigid with the handle to hold one of the arms fixed against independent movement with reference to the handle so that it will turn with the handle to facilitate the adjusting of the arms with 40 reference to each other, the other perforated ear U' of the arm S being loosely related to the handle and interposed between the perforated ear U and a washer V screwed to a part of said ear U and spaced therefrom as 45 shown, the two arms S being fastened in adjusted relation by a thumb nut or wheel W adapted by turning the same home to frictionally bind the two ears together between the washer and the shouldered portion ad- 50 joining the threaded stem of the handle thereof. To properly separate the arms S and massage elements carried thereby, it is simply necessary to loosen the binding nut or wheel W and to move one of the arms toward 55 and from the other either by holding the free arm and moving the other arm with the handle, or by holding the handle and arm fixed thereto stationary, and moving the free arm to the position desired, thereafter bind- 60 ing the locking nut or wheel in place as previously observed.

While I have herein disclosed a specific embodiment of the invention, it will be understood by persons skilled in the art that 65 said invention is capable of embodiment in

other forms and devices as may be embraced in the scope of the hereto appended claims.

What I claim is:

1. A massage device of the character described, comprising a handle, and a pair of 70 massage elements associated therewith and adjustable toward and from each other in a direction approximately around the axis of the handle.

2. A massage device of the character described, comprising a handle for shifting the device from place to place on the body and a pair of relatively flat massage elements carried by the handle, said elements being mounted for a freedom of movement to 80 be self adjustable in operation angularly with respect to the handle, substantially as described, in combination with means other than the handle for manipulating the massage elements. 85

3. A massage device of the character described, comprising a handle for shifting the device from place to place on the body and a pair of relatively flat massage elements carried by the handle, said elements being 90 mounted for a freedom of movement to be self adjustable in operation angularly with respect to the handle, and means for fixedly adjusting the massage element supports, with respect to the handle, in combination 95 with means other than the handle for manipulating the massage elements.

4. A massage device of the character described, comprising a handle for shifting the device from place to place on the body, an 100 arm projecting from the handle, and a relatively flat massage element pivoted to said arm adapted to change its position angularly with respect to the handle, in combination with means other than the handle for 105 manipulating the massage element.

5. A massage device of the character described, comprising a handle for shifting the device from place to place on the body, an arm projecting from the handle, a relatively 110 flat massage element pivoted to said arm adapted to change its position angularly with respect to the handle, and means for adjusting the position of the arm on the handle, in combination with means other 115 than the handle for manipulating the massage element.

6. A massage device of the character described, comprising a handle having a threaded stem, massage elements, arms connecting the massage elements to the handle, one of said arms being fast with the handle and the other movable with reference thereto, and means for securing the arms in relative adjusted position with the handle. 120

7. A massage device of the character described, comprising a pair of massage elements, a handle therefor, and means for connecting the massage elements to the handle comprising arms therebetween, one arm be- 125

ing fast with the handle and the other being pivoted for adjustment on the handle, and means for binding the arms together to secure them in relatively adjusted position.

5 8. A massage device of the character described, comprising a pair of massage elements, a handle therefor and means for connecting the massage elements to the handle comprising arms therebetween, one arm 10 being fast with the handle and the other being pivoted for adjustment on the handle, and means for binding the arms together to secure them in relatively adjusted position, said means including a binding nut having 15 threaded engagement with the handle adapted to impinge upon a washer carried by the fixed arm and spaced therefrom for the reception of the other arm.

9. A massage device for the character described, comprising a pair of massage elements, a handle, and arms connecting the massage elements to the handle, said arms having perforated portions adapted to engage over a part of the handle, one of said 25 perforated portions having a washer secured thereto and spaced therefrom for the reception of the other perforated portion, and means for binding the perforated portions together to secure the arms in approximate 30 spaced relation.

10. A massage device of the character described, comprising a handle, a pair of expansible massage elements carried by said handle and adapted to engage the part to be 35 treated from opposite positions, and means for alternately expanding and contracting said massage elements, substantially as and for the purpose described.

11. A massage device of the character described, comprising a handle, a pair of expansible massage elements carried by said handle and adapted to engage the part to be 40 treated from opposite positions, and means

for alternately expanding and contracting said massage elements, the massage elements 45 having a movable connection with the handle to enable automatic adjustment of said elements.

12. A massage device of the character described, comprising a pair of expansible 50 massage elements adapted to engage the part to be treated from opposite positions, means for supplying pulsating pressure to the expansible massage elements, and means for applying the massage device including 55 a handle, arms for connecting the handle to the massage elements, free pivotal connections between the outer ends of the handles of the arms and the massage elements and an adjustably fixed connection between the 60 inner ends of the arms and the handle.

13. A massage device of the character described, comprising a pair of opposing massage elements, a handle therefor, and means for fixedly adjusting said elements apart 65 and for permitting independent adjustment of said elements with reference to the handle.

14. A massage device of the character described, comprising a pair of massage elements movably related to each other and curved on their inner faces for the purpose 70 of conforming to and receiving the part to be treated, expansible parts overlying the said curved surfaces, and means for communicating air pressure to said expansible parts 75 to effect relatively alternating expansion and contraction thereof, substantially as described.

In testimony whereof I hereunto affix my 80 signature in the presence of two witnesses.

WILLIAM C. J. GUILFORD.
